UNITED STATES PATENT OFFICE.

GUSTAVE SOBOTKA AND ADOLPH KLIEMETSCHEK, OF NEW YORK, N. Y.,
ASSIGNORS TO FLEISCHMANN & CO., OF SAME PLACE.

METHOD OF AND APPARATUS FOR PURIFYING AND REGULATING THE TEMPERATURE OF AIR.

SPECIFICATION forming part of Letters Patent No. 471,294, dated March 22, 1892.

Application filed August 20, 1891. Serial No. 403,208. (No model.)

To all whom it may concern:

Be it known that we, GUSTAVE SOBOTKA and ADOLPH KLIEMETSCHEK, citizens of Austria-Hungary, residing at New York, in the county of New York and State of New York, have invented certain new and useful Improvements in the Method of and Apparatus for Purifying and Regulating the Temperature of Air; and we do hereby declare the following to be a full, clear, and exact description of the invention, such as will enable others skilled in the art to which it appertains to make and use the same.

Our invention relates to improvements in apparatus for purifying and regulating the temperature of air; and the object of the invention is to provide means for purifying air and simultaneously cooling or heating the same, whereby either hot, medium, or cold purified air may be delivered direct from the purifying apparatus into the desired receiver for charging purposes or for any of the various processes carried on in breweries, distilleries, and similar establishments.

Our invention will first be described in connection with the accompanying drawings and then pointed out in the claims at the end of this specification.

Referring to the drawings, Figure 1 represents a sectional side elevation of one form of apparatus which may be used for carrying our improved method into effect, and Fig. 2 is a detail sectional view of a portion of the dry filter shown at the right of Fig. 1.

A denotes a suitable tank or cylinder, which may contain water or other suitable liquid filtering media, as indicated at a.

B denotes a filter comprising a suitable casting, within which is placed a series of layers b of cotton or similar material, which is confined between perforated plates b', bolted to lugs or flanges b'', projecting from the interior of the cylinder.

C denotes a pump of any desired construction, which connects by means of pipes c c' with the lower portions of the filters A and B.

D denotes an upright cylinder or pipe-section, which serves as an air inlet or conduit, and which is connected by means of a short pipe-section D' with the top of the filter B, and which is provided at the lower end there-

of with an extension D² for a purpose to be described.

E denotes a suitable pipe, which may enter the inlet pipe or cylinder D near the lower portion thereof and which is bent so as to extend within the cylinder nearly the entire length thereof in a suitable coil or preferably up and down in a serpentine or zigzag course parallel with the cylinder, as shown at E', and its exit end connects by means of a pipe-section E² with a pipe E³, which extends vertically through the cylinder or filter A and is provided at the lower end thereof with a suitable coil E⁴, which preferably forms a continuation of the pipe E³ and terminates in an upright portion E⁵, which connects by means of a pipe-section E⁶ with a pipe F. The pipe F is provided with suitable valves f f', which are located above and below the point of connection with the pipe E⁶, respectively, as shown, and said pipe F communicates through the valve f' with a brine-pump G and through the valve f with the exhaust of a steam-engine or other suitable source of supply of a heating medium, which may be either gas or liquid under pressure. The pipe E³ is provided with an extension e, which opens into the outer air and is controlled by a suitable valve e', and the pipe E² is controlled by a suitable valve e².

H denotes an exhaust-pipe, which leads from the lowermost portion of the coil E⁴ to a suitable reservoir for the purpose of emptying the contents of the coil when desired, said pipe being controlled by a suitable valve h. The extension D² of the inlet pipe or cylinder D forms a chamber within which condensed water from the circulating-pipes E' may collect and be discharged through the short pipe-section d, provided with a valve d'.

The operation of our invention is as follows: The air entering the stand-pipe or cylinder D, as shown by the arrows, passes downward into the filter B, being drawn by the pump C through the cotton or other filtering media therein, and is forced into the lower portion of the filter A, and, rising therein through the water or other liquid filtering media, passes out through the exit-pipe A', from which it may be directed into a fermenter or any suitable receptacle containing the liquid to be charged, the pump C operat-

ing to draw in and force the air in the usual manner. If it is desired to heat the air simultaneously with its passage through the purifying apparatus, the valves f' and e^2 will be closed and the valves f and e' opened, and thereupon steam or other suitable heating medium may be caused to circulate through the pipes F , E^6 , E^5 , E^4 , and E^3 and out at the exit end e into the open air, thus heating the liquid in the cylinder A , which, being in contact with the air circulating through the same, will heat the air to the desired temperature. If now it be desired to cool the air simultaneously with its passage through the purifying apparatus, the valves f and e' are closed and the valves f' and e^2 are opened, and thereupon salt brine or other cooling medium may be forced by the pump G so as to circulate through the pipes E , E' , E^2 , F^3 , and E^4 , &c., and cool the air which circulates through the apparatus in contact therewith. To clear the pipes and coil of salt brine or other cooling-liquid therein, the valve h may be opened, and thereupon the liquid will flow through the pipe H into a suitable reservoir for that purpose. By this method the air which is to be injected into the fermented wort, beer, or other liquid to be charged is cleansed of all impurities and simultaneously cooled or heated to the desired temperature, and may be delivered by suitable pipe connections direct from the purifier in a moist state.

We are aware that it has heretofore been proposed to cleanse or purify air in quartz-mills, powder-mills, &c., by passing it through a liquid filtering medium and through screens with interposed layers of sponge or other porous material for the purpose of cleansing the air of dust and sand, that it has also been proposed for purposes of ventilation to supply air to railway-cars, dwellings, &c., by causing the air to pass into the apartment or car through pipes and water-tanks in contact with heat-circulating pipes or cooling media, the air being humidified by contact with the surface of the water, and such apparatus have been provided with fans for drawing the air from the humidifying-box and forcing it into the building. Hence we make no broad claim to such apparatus.

Having thus described our invention, what we claim as new, and desire to secure by Letters Patent, is—

55. 1. An apparatus for purifying and regulating the temperature of air, comprising the wet filter with fluid-circulating coils or pipes therein, valves for controlling the admission of a heating or cooling medium to said circulating-pipes, the stand-pipe, the circulating-pipes therein connecting with those of the wet filter, the dry filter, pipes or conduits connecting the latter filter with the wet filter below the water-line therein, an air-forcing apparatus arranged in the conduits connecting the two filters, and valves for controlling the flow through said circulating-pipes, whereby a col-

umn of dry filtered air may be forced into the liquid filtering medium and permitted to rise therein simultaneously with the circulation 70 of a cooling medium through circulating-pipes in contact with the filtered and unfiltered air, substantially as described.

2. An air-purifying and temperature-regulating apparatus comprising a dry filter, a 75 stand-pipe forming the inlet thereto, a fluid-circulating pipe or coil in said stand-pipe, a wet filter, a fluid-circulating pipe or coil in said wet filter communicating with the circulating-pipe in said stand-pipe and with source 80 of supply of both heating and cooling media, inlet and exhaust valves controlling the flow of fluid in said circulating-pipes, an air-forcing apparatus, and pipes or conduits connecting the exhaust of said dry filter with the inlet 85 to said wet filter below the water-line therein through said air-forcing apparatus, substantially as described.

3. In combination with the water-tank having the fluid-circulating pipe or coil therein 90 and means for forcing a heating or cooling medium through said circulating-pipe, the dry filter, the air-inlet pipe or conduit connecting with said dry filter, the fluid-circulating pipe in said inlet-pipe, bent in zigzag 95 form and connected by a suitable valve-controlled pipe with the fluid-circulating pipe in said water-tank, valves for controlling the flow of fluid in said circulating-pipes, and means for forcing the air in its passage from the dry 100 filter into the liquid filtering medium in said water-tank simultaneously with the circulation of a cooling medium in the pipes in contact with the incoming unfiltered air, substantially as described. 105

4. An apparatus for purifying and regulating the temperature of air, comprising the water-tank, the fluid-circulating coil or pipe in said tank, the valved pipe connecting said coil with sources of supply of both heating and cooling media, the dry filter, the stand-pipe forming the air-inlet to said dry filter, the circulating pipe or coil in said stand-pipe, the valved pipe connecting the circulating-pipes of the water-tank with those of the stand-pipe, the air-forcing apparatus connecting the two filters, and means for forcing a heating medium through the coil in said water-tank or filter or a cooling medium through the circulating systems in both the tank and the 110 stand-pipe, substantially as and for the purpose set forth. 115

5. An apparatus for purifying and regulating the temperature of air, comprising the wet filter, the fluid-circulating coil immersed in 120 said filter, the valved pipes connecting said coil with sources of supply of both heating and cooling media and with the exhaust therefrom, the dry filter, the air-pump, and conduits connecting the two filters, the stand-pipe with drip-chamber connecting with the inlet to said dry filter, the zigzag circulating-coil in said stand-pipe, the valved pipe connecting the circulating-coil of the wet filter 125 130

with the coil in the stand-pipe, and means for causing either a heating or a cooling medium to circulate through the coil in the wet filter in contact with the filtered air or a cooling medium to circulate through the coil in said wet filter and simultaneously through the coil in said stand-pipe in contact with the incoming unfiltered air, substantially as described.

In testimony whereof we affix our signatures in presence of two witnesses.
